Specification of Letters Patent. Patented Apr. 13, 1915.

Application filed March 24, 1910. Serial No. 551,287.

To all whom it may concern:

Be it known that I, ALFRED E. J. MAAGE, a citizen of the United States, residing at Milwaukee, in the county of Milwaukee and State of Wisconsin, have invented new and useful Improvements in Electric Switches, of which the following is a full, clear, concise, and exact description, reference being had to the accompanying drawing, forming a part of this specification.

My invention relates to improvements in electric switches and more particularly to snap switches.

It is the principal object of my invention to provide a simple compact and durable switch which may be actuated to both make and break circuit by successive movements of its operating member in the same direction.

My invention also has various other objects and advantages which will be herein-after set forth.

For the purpose of more fully disclosing the characteristic features of my invention, I shall describe the device illustrated in the accompanying drawing, which embodies one form of my invention as the same has been worked out in practice. It should be understood, however, that my invention is not limited to the particular structure illustrated, but is susceptible of various modifications.

In the accompanying drawing, Figure 1 is a longitudinal vertical sectional view through a lamp socket, having one form of my switch mechanism mounted therein; Fig. 2 is a transverse sectional view taken on line 2—2, Fig. 1; and Figs. 3, 4 and 5 are similar views of the switch mechanism illustrating the manner of operation thereof.

While I have shown my switch mechanism applied to a lamp socket, it should be understood that it may be used in various other relations. The lamp socket 6, which I have illustrated, is of a conventional type, and, therefore, need not be described. Within the socket 6 is an insulating base formed in two parts, 7 and 8 suitably spaced to form a recess 9 for the reception of the switch mechanism. Secured to the part 7 of the insulating base is a supporting plate 10 which may be conveniently formed with lugs 11 thereon adapted to be secured to the insulating base by screws 12, as best illustrated in

Fig. 2. The plate 10 has riveted, or otherwise secured thereto, a stud 13, upon which is pivoted the movable contact member 14. As illustrated, the member 14 is sector shaped and has secured thereto a resilient contact plate or finger 15. The contact plate 15 is adapted to be moved into and out of engagement with a spring contact 16 suitably located upon and secured to one of the members of the insulating base. In practice, the contact member 15 may be connected to one terminal of the controlled circuit or may be used to bridge two contacts similar to the contact 16 illustrated. The sector shaped member 14 has provided therein converging slots 18 and 19, separated by a portion 20, which preferably has its extremity 21 curved concentrically with the pivot stud 13.

The operating member for the switch comprises a frame 22 having an upwardly extending lug 23 arranged to work in a slot 24 in the supporting plate 10 as a guideway. The lug 23 preferably extends into a slot formed in the section 7 of the insulating base and is connected by a coil tension spring 25 to an angularly disposed lug 26 provided on the supporting plate 10. Hence, the operating member is biased to the left or rearwardly. The operating member is provided at its rear or left hand end with an upwardly extending pin 27 adapted to work in the slots 18 and 19 of the sector shaped member 14. The lower end of the pin 27 is preferably surrounded by an insulating sleeve 28 onto which is fitted a suitable clip 29 attached to the end of a suitable operating chain 30. While I have illustrated the switch mechanism as being operated by a chain, it should be understood that the operating member might be actuated by any other suitable means as, for instance, a push button.

In addition to the pin 27, I provide other connections between the operating member and the movable contact member which I shall now describe. A pawl 32 is arranged between the operating member and the sector shaped member 14, said pawl being provided at one end with a slot 33 through which passes the pin 27, and at its opposite end with a lug or hook portion 34 connected by a coil tension spring 35 to a lug 36 provided on the operating member 22. In

practice, I prefer to make the operating member 22 in the nature of a hollow frame in order that the spring 35 may be arranged within the same to produce a more compact structure. The pawl is further provided on opposite sides with laterally extending notched lugs 37 and 38 adapted, under the conditions hereinafter set forth, to respectively engage pins 39 and 40 carried by the 10 sector shaped member 14 on opposite sides of and in alinement with the pivot stud 13.

I shall now describe the operation of the switch mechanism with reference to Figs. 2, 3, 4 and 5. For the purposes of this description, let it be assumed that the parts of the 15 switch mechanism are in the positions illustrated in Fig. 2, in which the contact member 15 is out of engagement with the contact member 16 and the pin 27 of the operating member in the slot 19 of the sector shaped member 14. Under these conditions 20 it will be noted that the pin 27, being disposed in the slot 19, forms a locking means for maintaining the switch mechanism in 25 open position, for, obviously, the contact carrying member 14 cannot be moved until the pin 27 is withdrawn from the slot 19. Assuming now, that the operating member 30 is moved outwardly or toward the right, the pin 27 will be drawn toward the open end of the slot 19, while the pawl 32 will be moved into such a position that its lug 38 will engage the pin 40 on the contact member 14. The latter will occur, however, before 35 the pin 27 leaves the slot 19, thus causing the spring 35 to be tensioned, the pawl 32 in the meantime turning slightly on the pin 40 as its axis, as illustrated in Fig. 3. Also, as illustrated in Fig. 3, the pin 27 of 40 the operating member during this operation moves forwardly in the slot 33 in the pawl 32 until said pin 27 is drawn out of the slot 19 in the operating member, whereupon the tension of the spring 35 draws the 45 pawl 32 outwardly, thereby moving the contact member 14 into the position illustrated in Fig. 4. Of course, the shifting of the contact member 14 will occur instantaneously upon the release of the pin 27 from the slot 19, and, due to the energy stored 50 in the spring 35, said contact member is moved with a snap action. The parts will remain in the position shown in Fig. 4 until the operating member is released, whereupon 55 it will be immediately returned to initial position by the spring 25. In moving to initial position, the operating member carries the pin 27 into the slot 18 of the member 14, thus locking said member in 60 closed position as illustrated in Fig. 5. Also upon return of the operating member to initial position, the pawl 32 is released from the pin 40 and then centered by the spring 35 so that upon the next operation its lug 37 65 will engage the pin 39 of the member 14.

Here it should be noted that it is important that the spring 35 be made to return the pawl to the same position after each operation and that the pins 39 and 40 be so located that each will be engaged by the 70 pawl 32 when the contact member 14 is at one of the limits of its movement. It is further necessary that the parts be so proportioned that when the pawl is turned on one of the pins 39 or 40 as a fulcrum, said 75 pawl will clear the other of said pins.

The operation of the switch from closed to open position is similar to that previously described, and, therefore, requires no further discussion.

While my invention may be embodied in various other forms, the particular form illustrated is advantageous in that it may be formed almost entirely of stampings, and, when assembled, may be said to be self- 80 contained.

Having thus described my invention, what I desire to secure by Letters Patent is:—

1. In an electric switch, in combination, 90 an oscillating contact member, a reciprocating operating member therefor and a device bodily movable to directly engage said contact member on successive reciprocations of said operating member in the same direction to oscillate said contact member in opposite 95 directions, said device having a lost motion and energy storing connection with said operating member.

2. In an electric switch, in combination, 100 an oscillating contact member, a reciprocating operating member therefor a device directly engaging said contact member upon successive reciprocations of said operating member in the same direction to oscillate 105 said contact member in opposite directions, energy storing means connecting said device to said operating member, and means carried by said operating member engaging said contact member during a partial movement of the former to hold the latter against 110 movement until energy is stored in said energy storing means.

3. In an electric switch, in combination, 115 an oscillating contact member, a reciprocating operating member therefor, an operative 118 connection between said members comprising a pawl and a straight helical spring connecting said pawl to said operating member, and means for effecting an engagement of 120 said pawl with said contact member to oscillate the latter in opposite directions upon successive reciprocations of said operating member in the same direction.

4. In an electric switch, in combination, 125 an oscillating contact member, a reciprocating operating member therefor, an operative connection between said members comprising a pawl and a single helical spring connecting said pawl to said operating member, means for effecting an engagement 130

of said pawl with said contact member upon opposite sides of the pivot of the latter to oscillate the same in opposite directions upon successive reciprocations of said operating member in the same direction, and means carried by said operating member to hold said contact member against movement during a predetermined initial movement of the former to insure a snap movement of the latter during the influence of said pawl.

5. In an electric switch, in combination, an oscillating contact member, a reciprocating operating member therefor, a pawl having a pivotal lost motion connection with said operating member, a spring connecting said pawl to said operating member, means for alternately effecting an engagement of said pawl with said contact member on opposite sides of the pivot of the latter to oscillate the same in opposite directions upon successive reciprocations of said operating member in the same direction, and means holding said contact member against movement until said spring has been tensioned 20 to impart a snap movement to said contact member.

6. In an electric switch, in combination; an oscillating contact member, a reciprocating operating member, a pawl associated with said operating member to alternately engage parts of said contact member on opposite sides of its pivot upon successive reciprocations of said operating member in the same direction, a single spring connecting said operating member and said pawl to adjust the latter after each operation and means including said spring and pawl to impart a snap action to said contact member.

7. In an electric switch, in combination, an oscillatory contact member, a reciprocatory operating member, operative connecting means comprising a device having a lost motion connection with said contact member and a spring connecting said device and said operating member for causing oscillation of said contact member in alternately opposite directions upon successive movements of said operating member in one direction, and a single spring for restoring all 50 parts to operative position after each actuation of said contact member.

8. In an electric switch, in combination, an oscillatory contact member, a reciprocatory operating member, operative connecting means between the same, comprising a pawl having a lost motion connection with said contact member and a spring connecting said pawl and said operating member for effecting a snap oscillation of said contact member in alternately opposite directions upon successive movements of said operating member in one direction, and a spring for restoring all parts to proper positions after each actuation of said contact member, each of said springs comprising a

helix having a straight-line axis and being expansible, when tensioned, in the direction of its axis.

9. In an electric switch, in combination, a pivoted contact member, having radially disposed communicating slots therein, a reciprocating operating member having a portion working in the slots of said contact member to lock said contact member in its extreme positions upon reciprocation of said operating member in one direction and to hold said contact member against movement during a predetermined degree of movement of said operating member in the opposite direction, a pawl on said operating member having a pivoted and lost motion connection therewith, projections carried by said contact member on opposite sides of its pivot to be alternately engaged by said pawl upon successive reciprocation of said operating member in the same direction and a helical spring connecting the free end of said pawl to said operating member to cause said pawl to engage one or the other of the projections on said contact member and to have energy stored therein during operation of said operating member to impart a quick movement to said contact member when released by said operating member.

10. In an electric switch, in combination, an oscillating contact member, operating means therefor including a movable member one of said members having two spaced converging slots and a communicating slot connecting the same, a lug associated with said operating means extending through said slotted member and normally held within one of said converging slots, said slotted member and said lug being relatively movable and means for causing said lug to work from one of said converging slots through said communicating slot into the other of said converging slots upon successive operation in the same direction of said operating means to oscillate said contact member in opposite directions.

11. In an electric switch, in combination, an oscillating contact member, operating means therefor including a movable member, one of said members having two spaced converging slots and a communicating slot connecting the same, a lug associated with said operating means and extending through said slotted member, and a spring to normally hold said lug within one of said converging slots away from said communicating slot, said slotted member and said lug being relatively movable, and means for causing said lug to work from one of said converging slots through said communicating slot into the other of said converging slots upon successive operation in the same direction of said operating means to operate said contact member to alternately open and closed position.

12. In an electric switch, in combination, an oscillating contact member, operating means therefor including a movable member, one of said members having two spaced converging slots and a communicating slot connecting the same, a lug associated with said operating means and extending through said slotted member, a spring to normally hold said lug within one of said converging slots away from said communicating slot, said slotted member and said lug being relatively movable, and means for causing said lug to work from one of said converging slots through said communicating slot into the other of said converging slots upon suc-

cessive operation in the same direction of said operating means to operate said contact member to alternately open and closed position and means to move said slotted member with a snap action when said lug 2 enters said communicating slot from either of said converging slots.

In witness whereof, I have hereunto subscribed my name in the presence of two witnesses.

ALFRED E. J. MAAGE.
